UNITED STATES PATENT OFFICE.

WILLIAM H. SCOTT, OF HOLYOKE, MASSACHUSETTS, ASSIGNOR TO AMHERST WAXED PAPER MILLS, OF HOLYOKE, MASSACHUSETTS, A CORPORATION OF MASSACHUSETTS.

COATING-MACHINE.

1,299,388.

Specification of Letters Patent. Patented Apr. 1, 1919.

Application filed June 19, 1916. Serial No. 104,409.

To all whom it may concern:

Be it known that I, WILLIAM H. SCOTT, a citizen of the United States of America, residing at Holyoke, in the county of Hampden and State of Massachusetts, have invented certain new and useful Improvements in Coating-Machines, of which the following is a specification.

This invention relates to coating machines and more particularly to machines for coating paper with wax or other coating material.

In the general process of coating paper with wax, the web of paper is passed through a trough filled with heated wax; the coating there received is subsequently rubbed into the paper and polished, while still in a liquid condition; the polished coating of wax is thereafter set by immersing the web in a water trough; and finally the water adhering to the wax surface is removed.

An object of this invention is to provide, in a machine of the class described, an improved arrangement for removing the water from the waxed surface of the web, which comprises, guiding means to lead the web vertically upward from the water trough, whereby the water adhering to each side of the web may roll downwardly by gravity, and devices adjacent the web at a certain point in its vertical travel to prevent the passage beyond that point of the small quantities of water which still adhere to the web.

Another object of the invention is to provide, in a machine of the class described, improved devices to furnish blasts of air applied to the web in the direction of, against or at a right angle to the travel of the paper, the operation of which devices is particularly characterized by a "doctor" action to prevent the water adhering to the web from passing beyond the air blast beyond, as distinguished from a blowing action on the web to forcibly effect the removal of the water therefrom as by blowing it off the web.

Another object of the invention is to provide, in a machine of the class described, an improved flexible arrangement of the finishing devices, which is especially characterized in that, aside from the normal coating action involving the wax and water application, the devices may be quickly shifted to apply a "dry wax" coating without using

a water trough or a "one side" wax coating to the web without passing the web through either the wax or water troughs.

Another object of the invention is to provide in a wax coating machine an improved means of heating the "brushing" rolls, wherein radiation, as distinguished from conduction is employed, which permits improved results in close temperature regulation.

A further object of the invention is to provide in a wax coating machine dual winding and unwinding devices for the web to be coated, which are arranged, not only to permit a new web to be started into the machine in a minimum amount of time after the first web has been finished, but to permit the efficient operation of the machine when narrow rolls are used by simultaneously passing two narrow webs side by side through the machine.

Other objects and advantages will appear in the detailed description to follow and in the annexed claims.

Referring to the accompanying drawings, as illustrative of one preferred manner in which the invention may be practised—

Figure 1 is a side elevational view of the complete machine;

Fig. 2 is a sectional elevation thereof;

Fig. 3 is a detail view showing a reversing mechanism for certain of the finishing rolls;

Fig. 4 is a sectional elevation of the improved brushing roll;

Fig. 5 is a diagrammatical view illustrative of the air doctor arrangement;

Fig. 6 is a partial sectional plan view showing a detail of Fig. 5;

Fig. 7 is an end elevation of the dual winding machine;

Fig. 8 is a partial sectional view showing in detail the clutch used in the winding mechanism; and

Fig. 9 is a sectional elevation of the rear part of the machine showing a modification.

Referring to these drawings in detail and particularly to Fig. 2, A represents two spaced side frames from and between which the various rolls and devices are supported. At one end of the machine and on each frame A, a pair of adjustable bearings 1 (Fig. 1) are provided to removably support arbors 2, upon which rolls of paper to be coated may be placed. A web 3, taken

from a roll on either arbor 2, first passes to idler rolls 4 and 5, the former being horizontally adjustable by the hand wheel and screw as best shown in Fig. 1. This pair of 5 rolls serve to tension and smooth out any wrinkles in the web 3. The latter then passes downwardly under an idle roll 6, which is mounted on frames 7 vertically movable by means of a threaded rod 8 and 10 intermeshing spiral gears 9, when a hand wheel 10 is turned. The roll 6 normally is submerged in a trough 11 filled with melted wax, paraffin, or the like, which may be heated to the desired temperature by 15 steam passing through coils 13. Obviously, by raising or lowering roll 6, the travel of web 3 through trough 11 may be shortened or lengthened, as desired, to control the thickness of the coating of wax applied to 20 the web. If desired, the roll 6 may be raised entirely out of the trough 11, so that the web is not coated therein, for a reason which will later appear.

From the wax trough 11, the web passes 25 upwardly over a brushing roll 14, preferably of brass, which is vertically adjustable by means of a hand wheel 15, intermeshing spiral gears 16, and a threaded rod 17 in an obvious manner. This roll is heated by 30 improved means to be described and acts to keep the wax on web 3 at the proper temperature during its transit from the trough to the finishing rolls. From roll 14, the web passes to a series of three stacked rolls, 35 and normally between the lower and intermediate roll as illustrated, although it may be passed through the stack in different ways to effect various results in coating as will later appear. The upper and lower 40 rolls 18 and 19 are adapted to be heated either by steam or hot water in a well known manner. The intermediate roll 20 is preferably a solid roll and is adapted to be forced against roll 20 by means to be described. The coaction of rolls 19 and 20 45 serves to force the wax into web 3 and prevent surplus wax from passing along with the web. After the web leaves rolls 19 and 20, it passes over a relatively large roll 21, 50 which may be heated, as are rolls 19 and 20, or in certain operations it may be cooled by water as will later appear.

The web in leaving roll 21 passes vertically downward between two small rolls 22 and 23, preferably of brass and highly polished, which are heated by improved means to be described, as is the roll 14. Each of these rolls is horizontally movable in its bearings by the screws shown in Fig. 1 and 55 are preferably arranged to just brush the web with a slight lateral pressure. These rolls are driven by means to be described in the direction of travel of web 3 at a peripheral speed somewhat in excess of the surface speed of the web to obtain a brushing

action, whereby the coated surface may be polished. It is not essential that rolls 22 and 23 travel with the web, and they may as well be driven in the opposite direction for the only prerequisite for their effective 70 action is that there be a relative difference in speed to obtain a brushing action. From the brushing rolls, the web passes downwardly into a trough 24 filled with cold water to two spaced idler rolls 25, which are 75 rotatably mounted in frames 26. The latter are vertically movable on suitable standards by a hand wheel 27, intermeshing spiral gears 28, and threaded rods 29, in an obvious manner. It is to be understood that 80 the hand wheels 28, shown as applied on each side of the machine, are rigidly connected together to effect an equal and simultaneous movement of each frame 26, and the wheels 10, 15, and 18, already described, are 85 arranged in an analogous manner.

The web 3 in leaving the water trough 25 passes vertically upward to a roll 30 and during this travel the larger part of the water adhering to the waxed surface of the 90 web falls from each side thereof by gravity. As a matter of practice, the only water clinging to the paper after it has traversed the major portion of the distance to roll 30 is in the form of small drops and these 95 drops, if prevented from passing beyond a predetermined point, will be joined by other small drops to form larger drops. When the drops accumulate into a sufficient mass to break the force due to surface tension, 100 they will roll downwardly. To prevent the passage of the small drops, a tube 31 is applied on each side and closely adjacent web 3 at a distance slightly below roll 30. These tubes are supplied with air from pipes 32, 105 one on either side of the machine, and extend between the tubes entirely across web 3. As shown in Fig. 6, each tube 31 is rotatably mounted on a thimble 33 integral with pipe 32 so that the tubes may be turned at 110 any angle desired. Narrow slots 34, which extend substantially the entire length of the tubes, are formed therein as outlets for the air. The preferred method is to so turn tubes 31 that the air from outlets 34 is directed substantially at right angles to the travel of web 3, as best shown in Fig. 5. These blasts of air do not, in this position, blow the water from the paper but act as a barrier to the passage of the drops of water. 115 They may be, therefore, considered as "air" doctors and act in an analogous manner to the well known doctors used in the paper making art, which bear against and scrape a roll. Although the preferable method is 120 to direct the blast from tubes 31 and 37 at right angles to the web, the tubes may, if desired, be turned to direct the blast therefrom either against or with the travel of the web. From roll 30, the web travels to a roll 125 130

35 and preferably thence vertically upward to a roll 36. A pair of tubes 37, fed with air from pipes 32, are arranged in the same manner as are tubes 31 and act to dry the paper. A valve 38 is provided in pipe 32 to close off the supply from tubes 37 when desired. The web 3 passes from roll 36 or, if desired, directly from roll 35 to a horizontally adjustable roll 40 and thence over 10 either of a pair of winding arbors 42 which rolls and arbors are rotatably mounted in spaced side frames B.

The mechanism for winding the web on either arbor 42 will now be described with 15 particular reference to Figs. 7 and 8. Each arbor 42 has a squared end 45 adapted to be connected by a coupling member 46 to a squared end 47 on a short shaft 48. The coupling is freely slideable on the portion 47 20 and may be moved manually thereon by any suitable tool, which may be placed in the circumferential grooves shown. Loose on shafts 48 are gears 49 and slideably keyed to the shafts adjacent gears 49 are clutch elements 50 adapted to engage one face of the gears. The elements 50 may be forced into or out of engagement with gears 49 by hand wheels 51 and threaded rods 52 in an obvious manner. Each gear 49 is driven through a 25 pinion 55 from a single gear 56 (Fig. 1), the shaft of which is in turn driven by a pulley 57. The latter is driven by a belt 58 from the main driving shaft 59 of the machine, and the belt is preferably loose and arranged 30 to slip on its pulleys as the paper builds up on arbor 49. An adjustably mounted idler 60 permits regulation of the tension of belt 58 in an obvious manner.

The shaft 59 also drives by a sprocket 40 chain 63 the roll 21 and the latter drives by a chain 64 the roll 30. The latter and rolls 35 and 26 are connected by a chain 65 so that all are positively driven. An adjustable idler sprocket 66 serves to tighten chain 65 45 when desired. Fixed to the shaft of roll 35 is a grooved pulley 67 which drives by belts 68 and 69 (the latter being crossed or vice versa as desired) the brushing rolls 22 and 23, respectively. The main shaft 59 also 50 bears a pinion 70 (Fig. 3) and in mesh therewith is a pinion 71 mounted on a radius arm 72 loose on shaft 59. Also mounted on arm 72 and in mesh with pinion 71 is a pinion 73. Normally pinion 70 drives through pinion 71 55 a gear 74 which is fastened to and drives the lower roll 19 of the stack in the direction indicated in Fig. 2, and the latter drives roll 20 through frictional contact. However, as will be described, it is sometimes desirable to 60 drive roll 19 in the opposite direction and then the arm 72 may be swung to throw pinion 71 out of and pinion 73 into mesh with gear 74 so that the direction of the latter may be quickly reversed, when desired. 65 The rolls 18, 19, and 20 are slidably mount-

ed in suitable frames after the fashion of calender rolls, and the upper roll 18 is movable by a threaded rod 76 through intermeshing bevel gears 77, when either hand wheel 78 is turned, whereby pressure may be placed 70 thereon in a well known manner. Between the boxes for rolls 18 and 20 is a "jack" 79 which is simply a right and left hand threaded member in engagement with the boxes for rolls 18 and 20, respectively. Obviously, by 75 turning this jack the rolls 18 and 20 may be separated as shown in the drawings. When so separated, the pressure applied to roll 18 is communicated through jacks 79 to roll 20 and, when it is desired to lift the latter 80 slightly from roll 19, the movement of roll 18 lifts roll 20 by means of a pivoted hook 80 on each side engaging the latter.

The improved means of heating the rolls 14, 22, and 23 will now be described and 85 reference is made to Fig. 4. The roll is preferably a pipe or tube provided at each end with collars 83 threaded thereon. Where the roll is driven, as are rolls 22 and 23, the sprocket is fastened to the collar, as shown. 90 The arbor for the roll is a pipe 84, which extends entirely through the roll and is adapted to have steam passed therethrough. The collars 83 rotate freely on collars 85 threaded upon pipe 84, and the collars are 95 held axially in position by check nuts 86. Heretofore, steam has been passed directly to the interior of the heating roll used in this type of machine and, until it condensed, was not removed. It has been found that, with 100 direct heating, small rolls often become overheated and, since they are always filled with steam under pressure, the tendency is naturally for the temperature to increase. With the present method, however, the roll is 105 heated indirectly by radiation from pipe 84, and, since the flow therethrough can be readily controlled, the temperature regulation is improved, and it has been found in practice to be an especially advantageous 110 means for heating for the small rolls.

A modification of the means, for removing the water from web 3, is illustrated in Fig. 2 but is best shown in Fig. 9 to which particular reference will be made. The web 115 leaves bath 24 in a vertical direction as before and passes upwardly to and over roll 30. Roll 35 is, however, preferably omitted, and the web 3 passes from roll 30 directly to roll 36 and thence to roll 40 and 120 the winding mechanism. Rolls 30 and 36 are in this modification preferably arranged at different heights so that the web is inclined in the direction of its travel, as clearly shown in Fig. 9. Intermediate the vertical 125 travel of web 3 from roll 25 to roll 30 is an agitator 90 which is rotatably supported from frame A and may be driven by any suitable means, such as the belt 98, for example. The agitator has a plurality of 130

blades 91 which extend entirely across web 3 and are arranged periodically to strike the latter. An idler 92 is preferably arranged below the line of contact of blades 91 with 5 the web and steadies the latter against the slight blow from the blades. The web 3 is thus vibrated just sufficiently to shake off the drops of water thereon which are carried upwardly by adhesion from the water bath 24. The agitator 90 removes the major portion of the water from the web by its shaking action and all that remains is in the form of a fine film. The surface of the web after it has passed the agitator is, in 10 fact, merely damp, and this dampness or fine film of moisture is removed during the inclined upper travel of the web between rolls 30 and 36, by means now to be described. The spaced pipes 32, heretofore 15 described, each have depending therefrom vertical pipes 94 and 95 and mounted between the pairs of pipes 94 and 95 are tubes 96 and 97, respectively, which are similar in every respect to the tubes 31 formerly 20 described in detail. These tubes are arranged above and adjacent web 3 and are preferably so turned that the blast from the outlets thereof is directed against the travel of web 3, as shown in Fig. 9. They may, however, on account of their adjustable mounting 25 be turned to direct the blast at any other desired angle. The function of the blasts of air from tubes 96 and 97 is to remove the moisture remaining as a fine film upon the web by a process of evaporation as distinguished from a removal by blowing.

Agitator 90 may be used without the air doctors, as just described, or, if desired, it 30 may be interposed between the doctors 31 and roll 25 as shown in Fig. 2. It may also be dispensed with in the modification shown in Fig. 9, and the removal of all the water may be left to the blasts from tubes 96 and 97. In event the agitator 90 is not desired, 35 all that is necessary to render it inoperative is to slip off its driving belt 98 and turn the agitator so that none of the blades 91 contact with web 3.

The preferred operation of the machine 40 will now be described. A web 3 taken from a roll on either arbor 2 or, where narrow rolls of paper are used, a web from rolls on both arbors (to utilize efficiently the entire width of the machine) is first tensioned and 45 straightened by rolls 4 and 5. The desired thickness of wax is then placed on the web by submerging it to the required depth in trough 11. The coating is then rubbed into the web by the coaction of rolls 19 and 20 and 50 all excess wax repelled. The roll 14 serves to keep the temperature of the wax coating constant during the travel of the web from trough 11 to rolls 19 and 20 and, 55 after leaving the latter, roll 21 acts in an analogous manner to maintain the tempera-

ture. It is desirable to keep the wax at a constant temperature until the water trough is reached, when the coating polished by rolls 22 and 23 is immediately set. The travel of the web through trough 24 is variable to permit any desired degree of cooling. In leaving trough 24, the web passes vertically upward between the air doctors 31 and subsequently between the drying tubes 37 or past agitator 90 and tubes 96 and 91 and is thereafter wound up on arbors 42. The vertical passage of web 3 from trough 24 permits nearly all the water to roll downwardly into the trough, and the doctors 31 or agitator 90 prevent any small drops which rise that distance to pass farther, as already described. A particularly advantageous feature lies in the arrangement whereby the web 3 enters and leaves the water vertically, whereby each side of the web is uniformly and simultaneously 85 acted upon as distinguished from an inclined passage of the web wherein the web is not equally affected on both sides and the resultant finish differs accordingly. 90

While the former is one preferred method of operation, the machine is adapted for other operations which will now be briefly described. The roll 18 may be lowered into engagement with roll 20 and the web, after 95 passing through rolls 19 and 20, may be carried partially around the latter and passed between rolls 18 and 20. On leaving the roll 18, it passes over roll 21 as heretofore, but this roll would then be cooled by 100 a circulation of water, and the frame 26 would also be raised to remove the web from the water trough 24. The web is by this method subjected to an extra heating and a so-called dry wax finish is imparted to 105 the paper.

With rolls 18, 19, and 20, all in contact a third operation may be used whereby a "one side" wax finish may be applied. In 110 this operation, the web is passed between rolls 18 and 20 and thence to roll 21 which is cooled as just described. The water bath is not used in this operation, and the frame 7 is also raised so that the web does not pass through wax trough 11. The wax is carried 115 by roll 19 to roll 20, which deposits it on one side of the web. In this operation, the roll 21 is preferably cooled so that the coating immediately sets.

It has not been thought necessary to describe in detail the specific manner of mounting the various rolls nor the connections whereby the rolls are supplied with steam and hot or cold water as these devices are well known and generally well understood by those skilled in the art. 120

It is recognized that modifications may be made in the structure herein described for illustrative purposes without departing from the scope of the invention which is defined 130

by the appended claims rather than by the foregoing description of one preferred embodiment.

What I claim is—

5. 1. In a coating machine having means to coat a web of paper with heated wax or the like, means to finish and polish said coating and a water bath arranged to harden the finished coating, guiding means arranged to 10 carry the web vertically upward from the water bath, and devices to prevent the passage of globules of water with the web beyond a predetermined point in its vertical travel, all constructed and arranged so that 15 the water adhering to each side of the web may fall therefrom by gravity.
2. In a coating machine having means to coat a web of paper with heated wax or the like, means to finish said coating and a water 20 bath to harden the finished coating as the web passes therethrough, guiding means to lead the web vertically upward from the water bath arranged so that the water adhering to the web may roll downwardly 25 therefrom, and devices adjacent each side of the web at a predetermined point in its vertical travel to direct a blast of air thereon, said devices being characterized by a doctor 30 action on the web to prevent the passage of drops of water with the web.
3. A coating machine, comprising, in combination, means to coat a web of paper with melted wax or the like, means to finish said coating, a water bath arranged to harden the 35 finished coating, guiding devices to lead the web vertically downward from said finishing means into and through the water whereby each side of the web is equally and simultaneously acted upon, other guiding devices 40 to lead the web vertically upward out of the water bath, whereby the water adhering to the web may roll therefrom by gravity, and means adjacent the web at a point in its vertical travel to prevent the travel of drops of 45 water with the web beyond a predetermined point.
4. A coating machine, comprising, in combination, means to coat a web of paper with melted wax or the like, devices to finish and 50 polish said coating, a water bath to harden the polished coating, guiding means to lead the web from said devices vertically downwardly into and through said bath, whereby each side of the web is equally and simultaneously 55 acted upon, guiding means to carry the web vertically upward from said bath, whereby the water adhering to the web may roll therefrom, and devices adjacent each side of the web at a predetermined point in 60 its vertical travel to direct a blast of air thereon, said last-named devices arranged to prevent the passage of small drops of water with the web, other guiding means to lead the web downwardly and again vertically 65 upward and other devices adjacent each side

of the web at a point in its vertical travel to direct a blast of air thereon to dry the web.

5. A coating machine, comprising, in combination, means to coat a web of paper with wax or the like, means to finish and polish the web and to harden the polished coating, comprising a water bath, and means to remove the water from the web, comprising guiding devices to lead the web vertically 70 upward from the water bath, whereby the water rolls downwardly therefrom by gravity into the trough, and adjustable devices on each side of the web at a predetermined point in its vertical travel to direct a blast 75 of air thereon, said blasts of air being characterized by a doctor action on the web to hold back small drops of water and prevent their passage with the web.

6. In a coating machine, having means to surface coat a web of paper with melted wax or the like and means to cool and harden the coating, mechanism intermediate said means arranged to impregnate the surface coating into the web, comprising a series of rolls 80 stacked one above another in contiguous relation, alternate rolls of the series adapted to be heated, adjustable devices to apply pressure to said rolls arranged so that two or more of the rolls may be forced into contact 85 as desired and means to drive said rolls, all constructed and arranged so that the web may be passed between two or more rolls of said series to impart various finishes to the web, substantially as described.

7. In a coating machine having means to coat a web of paper with heated wax or the like, means to finish and polish said coating and a water bath arranged to harden the finished coating, guiding means to carry the 105 web vertically upward from the water bath, and a device arranged adjacent the vertical travel of the web to periodically vibrate the latter, whereby the water adhering to the web may be shaken therefrom and fall into 110 said bath.

8. In a coating machine having means to coat a web of paper with heated wax or the like, means to finish and polish said coating and a water bath arranged to harden the finished coating, guiding means to carry the web vertically upward from the water bath, a device arranged adjacent the vertical travel of the web to periodically vibrate the latter, whereby drops of water adhering to the web 115 may be shaken therefrom and prevented from passing beyond a predetermined point in the vertical travel of the web, and a plurality of devices located beyond said point and arranged to direct blasts of air on said 120 web whereby any moisture remaining thereon may be evaporated.

9. In a coating machine, a trough for coating material, a series of stacked rolls mounted adjacent said trough so that the lower roll 130

thereof dips into said coating material, mechanism to drive one roll of said series in either direction as desired, the remaining rolls arranged to be driven from the last-
5 named roll by contact, the upper and lower roll of the series adapted to be heated, means to apply pressure to the rolls of said series including means to separate one roll from the other as desired to render one or more

inoperative, and adjustable guiding devices 10 to lead a web to said rolls, all constructed and arranged so that one or more of the rolls of said series may be driven in either direction as desired and so that a coated web may be passed in various ways between and 15 around said rolls to impart various finishes to the web.

WM. H. SCOTT.
